UNITED STATES PATENT OFFICE.

ADAM PRIMAK, OF MILWAUKEE, WISCONSIN.

BELT BUCKLE.

Application filed September 26, 1925. Serial No. 53,812.

This invention relates to belt buckles.

Objects of this invention are to provide a buckle which will cooperate with the standard type of belt in a novel manner, and which will automatically lock the belt in adjusted position without requiring the operator to manipulate any tongue or fastening member, and to provide a belt which will unlock automatically when the belt is manipulated in a certain predetermined manner.

Further objects are to provide a belt buckle in which all of the operating parts are hidden by the front of the buckle, and in which a very pleasing and attractive appearance is produced by this construction.

An embodiment of the invention is shown in the accompanying drawings, in which:—

Figure 1 is a front view of the buckle applied to a belt.

Figure 2 is a sectional view on the line 2—2 of Figure 1.

Figure 3 is a rear view of the buckle detached from the belt.

Referring to the drawings, it will be seen that the buckle comprises a main or body portion consisting of an outer plate 1 having inwardly turned upper and lower flanges 2. Preferably, these flanges are made integral with the face of the buckle and also the face is preferably curved, as illustrated in Figure 2, to accommodate itself to the curvature of the body.

A latch is pivotally mounted between the flanges 2 and comprises an inwardly turned short arm 3 preferably provided with teeth adapted to bite into the nonadjustable end 4 of the belt. This arm is integrally connected with a longer arm 5 to permit manipulation of the latch. It is to be noted from Figures 2 and 3 that when the latch is in its normal or locked position that the arm 5 contacts with the inner face of the plate 1.

The other end of the buckle is provided with a pintle pin 6 upon which a fluted or corrugated roller 7 is mounted. Preferably, this roller is formed by a rolled portion of sheet metal and the metal is continued outwardly to form a narrow attaching tongue 8, such tongue being curved inwardly towards the plate 1 when it is in its normal position.

In using the buckle, the free end of the strap 4 is passed between the fluted or corrugated roller 7 and the plate 1 and slides over the arm 5 of the latch. This motion of the belt causes the roller to rotate in a 55 counterclockwise direction, as viewed in Figure 2, and to thus rock the tongue 8 upwardly and permit the free insertion of the belt end. However, when the desired adjustment has been made, the belt end is permitted to slide 60 outwardly a slight distance, thus rotating the roller in the opposite direction and force the tongue 8 against the belt end.

The tongue 8 seats within one of the apertures 9 formed in the belt end, and locks the belt temporarily in the desired adjusted position without requiring any manipulation on the part of the operator.

Preferably an eyelet, such as indicated at 10, is formed upon the body portion adjacent 70 one end thereof, preferably the right hand end, when it is in position upon the wearer. This eyelet is adapted to receive the watch chain and forms a very simple and effective means of attaching the watch.

It will be seen, therefore, that a very simple type of buckle has been provided which functions in a novel and serviceable manner to lock the belt in position, and it will be seen further that the latch for locking the buckle 80 to any desired belt strap aids also in deflecting the end of the belt to prevent entangling of such end with any portion of the buckle.

Although the invention has been described 85 in considerable detail, it is to be understood that the invention may be variously embodied and is, therefore, to be limited only as claimed.

I claim:

The combination of a belt having an apertured end and having a plain end, of a buckle consisting of a body plate having rearwardly directed flanges, a latch pivoted between said flanges and adapted to engage the plain end 95 of the belt, said latch having a manipulating arm adapted to contact with the inner surface of the body plate and form a deflecting member for the free apertured end of the belt, a pintle pin extending between said 100

flanges, a roller mounted upon said pintle pin and having corrugations therein and adapted to receive the apertured free end of the belt between itself and the body plate, 5 said roller having a curved projecting tongue adapted to project into an aperture in said belt when said roller is rotated by the move- ment of said belt, said roller and tongue being integral and formed from sheet metal. In testimony that I claim the foregoing I ¹⁰ have hereunto set my hand at Milwaukee, in the county of Milwaukee and State of Wisconsin.

ADAM PRIMAK.
